DESIGN FOR A DRY SHAVER CASING

Georges Wilmet, New York, N. Y., assignor to American Safety Razor Corporation, Brooklyn,
N. Y., a corporation of Virginia

Application October 16, 1937, Serial No. 72,233

Term of patent 14 years

To all whom it may concern:

Be it known that I, Georges Wilmet, a subject of the King of Belgium and a resident of the city, county, and State of New York, have invented a new, original, and ornamental Design for a Dry Shaver Casing, of which the following is a specification, reference being had to the accompanying drawing, forming part thereof.

Figure 1 is a front elevational view of a dry
shaver casing showing my new design;

Figure 2 is a side elevational view thereof;
Figure 3 is a rear elevational view; and

I claim:

The ornamental design for a dry shaver casing
as shown.

GEORGES WILMET.
